May. 1348

Charles J. Woolson of Cleveland, Ohio.
Letters Patent No. 1348. Dated Decr. 4, 1860.

The schedule referred to in these ^{num} Letters Patent and making part of the same.
^{num}

Dec. 1348

To all whom it may concern:

Be it known that I, Charles J. Woolson, of Cleveland, Cuyahoga Co. Ohio, have invented and produced a new and useful design for the side of a Cooking Stove, including the doors to the fire arch and the oven; and I hereby declare that the following is a full and exact description thereof, reference being had to the accompanying drawing, in which my ornamental design is clearly represented;

The shape and configuration of the plates is designated by the general outline of the drawing.

The ornament upon the Doors is seen at A. A. The ornament upon the legs is seen at B. B.

Having thus distinctly represented and described the nature and arrangement of the ornamental work upon the side of the Cooking Stove.

What I claim therein as new, and desire to secure by Letters Patent, is the configuration and arrangement of said ornament, as herein designated and represented.

Witnessed:
